UNITED STATES PATENT OFFICE.

JOHN A. AKIN, OF NORTH LITTLE ROCK, ARKANSAS.

GARMENT-CUFF.

1,296,733.

Specification of Letters Patent. Patented Mar. 11, 1919.

Application filed July 15, 1918. Serial No. 244,962.

To all whom it may concern:

Be it known that I, JOHN A. AKIN, a citizen of the United States, residing at North Little Rock, in the county of Pulaski and State of Arkansas, have invented certain new and useful Improvements in Garment-Cuffs, of which the following is a specification, reference being had to the accompanying drawings.

- 10 This invention relates to shirts or other garments, and particularly to cuffs, and the general object is to provide a garment with a cuff, which cuff can be adjusted into three positions of wear, thus permitting the garment to be worn longer without laundrying, saving expense and wear thereof, and also conserving the garment for the reason that it is the cuffs of a shirt and like garments which wear out first.
- 20 These objects are obtained by the provision of a cuff of a very simple form so designed as to require but a minimum of material, and so designed that the cuff may be turned into three wearing positions.
- 25 Further objects are to provide for simplicity of construction, ease of manipulation and another object is to provide a cuff which will not be bulky or cumbersome in use, but will fit properly at all times.
- 30 My invention is illustrated in the accompanying drawings wherein:—

Figure 1 is a plan view of the blank from which my improved cuff is made.

Fig. 2 is a plan view showing the blank folded and applied to a shirt;

Fig. 2^a is a sectional view on the line 2^a—2^a of Fig. 2;

Figs. 3, 4 and 5 are perspective views showing three different positions of the cuff in use.

Referring to Figs. 1 and 2, which show the blank from which the cuff is made, it will be seen that the blank 10 is rectangular in plan and is approximately square. I do not, of course, wish to be limited however to any particular dimensions for the two sides of the blank. This blank, which may be made of linen, cotton, silk, or any other suitable material to suit the shirt or other garment with which the cuff is to be worn, is first folded over as at 11 to form a seam, which provides a finished appearance when the cuff is attached to the sleeve. This portion 11 is folded from the right side of the

material. The material of the cuff is divided into the surfaces or sections A, B and C.

The surface A extends from the turned edge 11 of the cuff and is two-thirds of the surface of the entire cuff. The section C is one-third the entire surface of the cuff. The sections A and C are defined by a row of stitching 12 around the cuff and makes the cuff ready to turn, whether the cuff is lined or unlined. The section B is defined by a row of stitching 13 which finishes the cuff and makes it ready to attach to the garment sleeve and extends entirely around the cuff after it has been turned. The section A is folded over upon the section B with its seam 10 disposed upon the section C in the manner illustrated in Fig. 1.

The complete cuff is attached to the garment sleeve by a row of stitching along the line 14. The stitched blank is now formed with the button-holes 15 in sections A and B and with the button-holes 16 in the sections B and C. In other words, there are button-holes at all four corners of the folded and stitched blank, and in such positions as may be best suited to the different styles of cuffs. After the cuff blank has been formed in the manner heretofore described, it is stitched to the extremity of the sleeve 17 by the stitching 14, the margin of the sleeve being inserted between the sections A and C and being stitched through the sleeve and the sections A, C and B as in Fig. 2. It will now be seen that the section A is normally on the outside of the sleeve, the section B on the inside of the sleeve, and extending down below the line of stitching 14 while the section C is on the inside of the lower portion of the section B and faces the interior face of the sleeve. The sleeve is likewise provided with two pairs of button-holes 18 and 19 in the facings thereof.

The button-holes 18 are spaced inwardly from the stitching 14 a distance equal to the distance between said stitching 14 and the button-holes 16 in the cuff. The button-holes 19 are spaced from the stitching 14 a distance equal to the distance between the stitching 14 and the button-holes 15.

By referring to Figs. 3 to 5 the manner in which the cuff is worn in its several positions will be fully understood. What I will term the first position of the cuff is illus-

trated in Fig. 3 and in this position the cuff is folded so that the section A, or surface A, faces the shirt sleeve, the section B facing toward the outside and forming the display portion of the cuff, while the section C faces toward the wrist of the wearer. Under these circumstances the cuff link is passed through the button-holes 16. With the cuff in this position it is to be noted that the button-holes 15 in the cuff will register with the button-holes 19 in the sleeve facings, so that a supplemental button may be disposed therethrough in order to maintain the cuff in such position as to afford no hindrance or obstruction to the removal of the sleeve 17 and the cuff through the sleeve of a coat or other garment.

The second position of the cuff is illustrated in Fig. 4. In this case the section C is turned inward to face inside of the sleeve of the shirt, thus causing the section B to be folded on the dotted line b so that only that portion B' of the cuff is displayed. Under these circumstances the sleeve link is passed through all four of the button-holes in the cuff and through the button-holes 18 of the sleeve. It will be seen therefore that the soiled outer surface of the cuff is concealed and a new surface displayed and that the soiled inner surface of the cuff is turned inward.

In the third position of the cuff as illustrated in Fig. 5 the section A is faced outward and the section B is inward against the wrist, while the section C faces the inner face of the sleeve. The cuff links are then passed through the button-holes 15. It will be noted that the point of attachment of the garment sleeve to the cuff is along a line one-third of the width of the cuff from the upper edge of the cuff, and two-thirds of the distance from the lower edge of the cuff, when the cuff is in its third position as illustrated in Fig. 5. With this position of the cuff the button-holes 16 will register with the button-holes 18 in the sleeve facings and through which registering button-holes a supplemental button may be disposed to facilitate the use of the cuff in this particular arrangement.

I am aware that the broad idea of the folded cuff so made as to be used a plurality of times is not new with me. For instance, the patent to S. E. Kalfus, 1,259,872 shows a cuff of this character which is intended to be worn in three different positions, that is, has three wearing surfaces, but the cuff is so designed that in all positions of the cuff there is a triple-ply around the wrist, whereas my cuff is so constructed that in two of the wearing positions there is only a single ply of material around the wrist, and in only one position is there a double ply or fold of material.

If the Kalfus cuff becomes saturated with

perspiration, grease, or is otherwise soiled, it will be unsightly even when folded or turned, while my cuff will still have two other entirely clean wearing surfaces when the third surface is dirty. Furthermore, in 70 the Kalfus cuff inasmuch as it is used at all times as a folded cuff, that is, with the triple fold around the wrist, the same edges of material will be forced against the hand at all times. Therefore, this edge will be 75 soiled in the same place at each wearing and the hardest rubbing will be necessary at this edge to clean the cuff in washing and the greatest strain will be on the same edge at all times when ironing, as it is to be ironed 80 folded. Thus the greatest wear in washing, ironing and wearing, will be along this single edge at the fold of the cuff, making it fray and wear out sooner than the garment will wear. Then, too, a cuff refolded 85 in the same crease is unsightly.

With my improved cuff, one edge is worn and soiled, then the cuff folded in the middle, then the other edge turned down in position, making three separate and distinct 90 edges or margins to come in contact with the hand, thus distributing the wear over the cuff and making it wear practically three times as long as it would if at all times folded upon a median line. Furthermore, 95 my cuff is ironed flat which is much easier to accomplish and is less wearing on the cuff. The Kalfus cuff, furthermore, takes approximately double the material that is required in making my cuff and by actual 100 test takes about three times as long to cut out and stitch, for in the Kalfus cuff there are five pieces of material when the cuff is lined and four pieces of material when the cuff is unlined, while my improved cuff only 105 requires two pieces of material when lined, and only one piece when unlined. Furthermore, with the Kalfus cuff, either lined or unlined, it is absolutely necessary that the stitching on each section of the cuff both 110 before and after turning shall start and stop at a certain specified point, and there are nine individual rows of stitching to be made, as aforesaid, five being made before the cuff is turned and four after turning. This re- 115 quires time and skill, while in my cuff, whether lined or unlined, there are only two rows of stitching necessary. These may begin at one corner and extend entirely around the cuff to the starting point, one before and one after the cuff is turned. Thus I secure 120 economy in material and time, reduction in cost and simplicity of construction.

Furthermore, in wearing the Kalfus cuff, 125 cuff buttons must be inserted in six button-holes at the first wearing and when changing cuffs, that is, changing the position of the cuffs, the cuff button must be taken out of six button-holes and replaced in six button-holes and this is necessary with each 130

change, while with my improved cuff, only two button-holes are used for two positions of the cuff and four button-holes when the cuff is folded into the third position. In 5 the Kalfus cuff the button passes through eighteen plies of the material when the cuff is lined and sixteen plies of material when unlined. This makes eight or nine layers of cloth worn around the wrist at all times, 10 whereas, in my improved cuff there are only six plies of material around the wrist, assuming that the cuff is lined, and only four plies of material when the cuff is unlined. So in two positions of the cuff there are 15 only two or three plies of material around the wrist, while in the third or folded position there are only four or six plies of material. Therefore, my cuff is not bulky or unpleasant to wear. 20 It will be obvious that modifications may be made in the details of my cuff without changing the scope of the invention, and that the cuff may be made with or without a lining, and of one ply of material or more. 25 The cuff may be made of any kind of material and may be made either soft or starched, but if the cuff is starched, it must be so treated that it may be folded in the middle, if desired to be worn as in Fig. 4 30 so as not to injure the texture of the material when folded.

Having described my invention, what I claim is:

In combination with a garment sleeve provided at its outer end with a longitudinally disposed facing, and with longitudinally spaced pairs of button-holes in said facing, a foldable cuff attached to the outer end of the sleeve and comprising a ply of material having button-holes at its four 40 corners, said cuff being attached to the sleeve at a point approximately one-third of the width of the cuff, the distance between the point of attachment of the cuff, and a pair of button-holes at one side thereof being 45 substantially equal to the distance between said point of attachment of the cuff and the innermost pair of button-holes in the facings of the sleeve, and the second pair of button-holes in the cuff being spaced a distance from the point of attachment of the cuff substantially equal to the distance between the point of attachment of the cuff and the outermost button-holes in the facings of the sleeve. 50

In testimony whereof I hereunto affix my signature in the presence of two witnesses.

JOHN A. AKIN.
